Primary Examiner — Mary Ann Calabrese*Assistant Examiner* — Harper E Comstock(74) *Attorney, Agent, or Firm* — Bradley J. Shelowitz(57) **CLAIM**

The ornamental design for a cushion, as shown and described.

DESCRIPTION

FIG. 1 is a top perspective view of a cushion in accordance with the present design;

FIG. 2 is a bottom perspective view thereof;

FIG. 3 is a top view thereof;

FIG. 4 is a bottom view thereof;

FIGS. 5-8 are left side, right side, front side, and rear side views thereof, respectively; and,

FIG. 9 is a cross-sectional view taken along line 9-9 in FIG. 1.

The broken lines showing parts of the cushion are for the purpose of illustrating portions of the cushion that form no part of the claimed design.

1 Claim, 6 Drawing Sheets(56)
